Primary Examiner—Catherine Tuttle(74) *Attorney, Agent, or Firm*—Karen E. Klumas(57) **CLAIM**

The ornamental design for an aerosol container, as shown and described.

DESCRIPTION

FIG. 1 is a perspective view of an aerosol container showing our new design in its closed position;

FIG. 2 is a perspective view showing our design in its opened position;

FIG. 3 is an elevational view of FIG. 1, seen in the direction of arrow 3;

FIG. 4 an elevational of FIG. 2 seen in the direction of arrow 4;

FIG. 5 is a top plan view of FIG. 1; and,

FIG. 6 is a bottom plan view of the design.
